Primary Examiner — Mimosa De

(74) Attorney, Agent, or Firm — Lewis Roca Rothgerber
Christie LLP(57) **CLAIM**

The ornamental design for an automotive headrest, as shown and described.

DESCRIPTION

FIG. 1 is a perspective view of an automotive headrest with a display in an unrolled state;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of the automotive headrest with the display in a rolled state;

FIG. 9 is a front view thereof;

FIG. 10 is a rear view thereof;

FIG. 11 is a left-side view thereof;

FIG. 12 is a right-side view thereof;

FIG. 13 is a top view thereof;

FIG. 14 is a bottom view thereof; and,

FIG. 15 is a front view of the automotive headrest with the display in the unrolled state on which an image is displayed in dotted lines, the image forming no part of the claimed design.
